UNITED STATES PATENT OFFICE.

GEORGE E. CAMPBELL, OF CHATTANOOGA, TENNESSEE, ASSIGNOR TO THE WHELAND COMPANY, OF CHATTANOOGA, TENNESSEE, A CORPORATION OF TENNESSEE.

COMBINED SETWORK AND RECEDER FOR SAWMILL CARRIAGES.

Application filed September 24, 1924. Serial No. 739,636.

This invention relates to combined set-works and recede for saw mill carriages, the object being to combine into one unit the hand-operated set-works, spring-recede and brake, and to operate all of these functions with one lever suitable for use on a saw-mill carriage.

Another object of my invention is the arrangement of the control of the ratchet pawls and the brake for the setworks, whereby the pawls are always lifted from the ratchet wheel before the brake is released and the brake is always applied before the pawls are dropped into place, eliminating the possibility of ripping off the ratchet teeth.

In the drawings:—

Fig. 1 is a side elevation of the sawmill setworks mounted on the carriage; 20 Fig. 2 is an end view of the same;

Fig. 3 is an enlarged side elevation, partly in section, of the pawl and ratchet mechanism;

Fig. 4 is an end view of the mechanism 25 shown in Fig. 3;

Fig. 5 is a plan view of the quadrant cap; and

Fig. 6 is a detail plan view of the pawls. The numerals 1—1 indicate the rails; 2, 30 the carriage mounted upon suitable wheels 3—3 adapted to travel upon the rails 1—1.

Arranged transversely of the carriage at either end thereof are guideways 4 upon which are slidably mounted the headblock 35 knees 5. Journaled in the guideways 4 is a drive-shaft 6 extending longitudinally of the carriage, and keyed thereto at each end is a gearwheel 7 adapted to mesh with the 40 cogs 8 on the under side of the headblock 5 knees 5, the rotation of the shaft 6 causing the knees 5 to advance or recede upon the carriage.

As a means for operating the knees as described, I preferably provide the following 45 mechanism:

Keyed to the shaft 6 is a ratchet-wheel 9, the periphery of which is provided centrally thereof with ratchet teeth 10, the edges 11—11 serving as braking surfaces.

50 The shaft 6 is supported on opposite sides of the ratchet-wheel 9 by suitable bearings 12—12 integral with a base 13 mounted upon the carriage 2. Extending rearwardly from the base 13 are brackets 14—14 upon

which are pivotally mounted the check-pawls 15—15, there being two abreast, and one a trifle shorter than the other whereby a finer adjustment may be had. It is obvious that one would suffice. A brake shoe 16 bearing normally against the braking drums 11 adjacent the ratchet-wheel 9 is pivotally mounted upon one end of a bell-crank lever 17 upon a pin 17' journaled in suitable bearings 18 adjustably mounted in slots 19 in the brackets 14—14. The lower end of the bell-crank lever 17 is provided with a weight 20 which acts normally to hold the brake shoe 16 against the ratchet-wheel.

The numeral 21 indicates a pawl set lever, 70 forked at its lower end to straddle the ratchet-wheel 9, the lower ends of the forked member being pivoted to the shaft 6. A pair of advance ratchet-pawls 22 are pivoted to the pawl lever 21 and engage the ratchet-wheel 9, the pawls being of different lengths whereby a finer adjustment may be made. The numeral 23 indicates a pawl lifter pivoted upon the pin 17' and extending beneath a laterally projecting lug 15' of the 75 check-pawls 15, and beneath a laterally extending lug 22' of one of the advance pawls 22. Extending forwardly from the pawl-lever 21 is a pull-rod 24 provided with a handle 25 serving in one instance as a means 80 for actuating the pawl-lever 21. This pull-rod 24 is rotatably journaled in a bracket 26 secured to the upper end of the pawl-lever 21. The outer end of the pull-rod is turned down to form an arm 27 which is connected 85 by a chain 28 to the outer end of the pawl-lifter 23. An arm 29 extending downwardly from the pawl-lifter 23 is aligned with a lug 30 formed on the bell-crank brake lever.

After the pawl-lifter has raised the pawls 90 from the ratchet-wheel 9, by the rotation of the pull-rod 24, the arm 29 serves to release the brake-shoes 16, releasing the ratchet-wheel 9. It will be observed that the downward movement of the pawl-lifter 23 again 100 applies the brake before the pawls are let down into engagement with the ratchet-wheel, thereby preventing the possibility of destroying the teeth of the ratchet-wheel.

As a means for regulating the movement 105 of the pawl-lever 21, I preferably provide a quadrant cap 31, the base of which forms a cap 32 for one of the bearings 12. The

face of the quadrant cap is provided with a plurality of staggered openings 33 to receive a pin 34 which is engaged by a lug 35 on the pawl-lever 21 for limiting its movement in one direction, while an adjustable set-screw 36 at the opposite end of said quadrant 31 limits the movement of the pawl-lever 21 in the opposite direction.

As the knees 5 are advanced by the rotation of the shaft 6, a spiral recede spring 37 secured at its outer end to the shaft 6 by means of a collar 38, and at its inner end to the base 13, is wound up, keeping the ratchet-wheels under tension, the latter when released by the brake 16 serving to recede the knees back from the saw.

As noticed in Fig. 3, the recede spring 37 imparts a backward motion to the brake 11 as indicated by the dotted arrow A, the action being such that the minute the recede spring applies power in this direction the brake shoe 16 grasps tightly with a wedging effect; due to the toggle action of the link 17 and weight 20, this toggle action is always positive and automatically opposed to the spring action. On the other hand when the operator desires to advance the knees by pulling forward the lever 21 in the direction of the arrow B, the brake, due to the toggle action, offers very little resistance.

In operation, the knees 5 are receded, and a log placed in position whereupon the pawl-lever 21 is actuated by the pull-rod 24, to advance the log step by step as the boards are sawed. As the ratchet-wheel 9 is rotated to cause this advance, the spiral spring 37 is wound up, the pawls 15 and the brake 16 preventing the rotation of the ratchet-wheel 9 in the opposite direction. When it is desired to recede the knees, the operator rotates the pull-rod 24 whereupon the pawl-lifter is raised disengaging both sets of pawls 15 and 22 from the ratchet-wheel 9. The brake 16, however, still engages the ratchet-wheel 9 preventing its rotation in the backward direction. A further upward movement of the pawl-lifter 23 causes the arm 29 to engage the lug 30 of the brake bell-crank lever, releasing the ratchet-wheel 9, permitting the knees 5 to recede from the saw. The pawl-lifter is then lowered, first disengaging the brake-shoe 16, setting the brake, after which a further downward movement permits the pawls again to engage the ratchet-wheel 9.

I claim:

1. In a sawmill setworks, the combination with headblock knees, a shaft carrying a pinion engaging therewith, a ratchet-wheel and brake-drum keyed to said shaft, a check-pawl engaging said ratchet-wheel, a pivoted pawl lever, a pawl engaging said ratchet-wheel to impart movement thereto in one direction, a brake-shoe engaging said brake-drum adapted normally to prevent the ro-

tion of said drum in the opposite direction, and means for disengaging said pawls and operating said brake-shoe.

2. In a sawmill setworks, the combination with headblock knees, a shaft carrying a pinion engaging therewith, a ratchet-wheel and brake drum keyed to said shaft, a check-pawl engaging said ratchet-wheel, a pivoted pawl lever, a pawl engaging said ratchet-wheel to impart movement thereto in one direction, a brake-shoe engaging said brake drum adapted normally to prevent the rotation of said drum in the opposite direction, a pull-rod pivoted for rotary movement upon the outer end of said pawl lever, and means connected to said rotary pull rod for raising said pawls and operating said brake.

3. In a sawmill setworks, the combination with headblock knees, a shaft carrying a pinion engaging therewith, a ratchet-wheel and brake-drum keyed to said shaft, a spring fixed at one end and secured to said shaft at its opposite end, a pivoted check-pawl engaging said ratchet-wheel, a pivoted pawl lever carrying a pawl engaging and adapted to rotate said ratchet-wheel against the tension of said spring, a brake shoe normally held against said brake drum to prevent its rotation in one direction, a pull-rod rotatably mounted at the outer end of said pawl lever, a pawl-lifter actuated by said rotary pull-rod for progressively lifting said pawls and operating said brake.

4. In a sawmill setworks, the combination with headblock knees, a shaft carrying a pinion engaging therewith, a ratchet-wheel and brake drum keyed to said shaft, a spring fixed at one end and secured to said shaft at its opposite end, a pivoted check-pawl engaging said ratchet-wheel, a pivoted pawl lever carrying a pawl engaging said ratchet-wheel adapted to rotate said ratchet-wheel against the tension of said spring, a pivoted bell-crank, a brake-shoe pivoted thereto adapted normally to rest against said brake-drum to prevent its rotation against the tension of said spring, a pull-rod rotatably mounted at the outer end of said pawl-lever, a pivoted pawl-lifter arranged beneath said pawls, said pawl-lifter having a lug adapted to engage said bell-crank whereby the pawls are raised and the brake disengaged from said brake-drum.

5. In a sawmill setworks, the combination of a set shaft, a ratchet wheel, and brake-drum keyed to said shaft, pawls engaging said ratchet-wheel, a brake-shoe engaging the brake-drum adapted automatically to prevent the backward rotation of the drum, and combined means for progressively disengaging the pawls and operating the brake.

6. In a saw-mill setworks, the combination of a set shaft, means for selectively moving said set shaft forward, a brake drum for said shaft, a brake shoe for engaging the

brake drum to automatically apply a braking power to said set shaft, and combined means for progressively disengaging the forward moving means and for operating the 5 brake.

7. In a saw-mill setworks, the combination of a set shaft, means for moving said set shaft forward, a brake drum for said set shaft, a brake shoe in position to engage the 10 brake drum to automatically prevent back motion of the set shaft, and means for progressively disengaging the forward operating means and for operating the brake shoe.

8. In a saw-mill setworks, the combination 15 of a set shaft, means for moving said set shaft forward, a brake drum for said set shaft, a brake shoe in position to engage said drum to automatically prevent back motion of the set shaft, and means for engaging 20 and disengaging said forward operating means and for applying the brake, said means applying said brake prior to the engagement of said forward operating means.

9. In a sawmill setworks, the combination

of a set shaft, means for moving said set shaft forward, a brake drum for said set shaft, a brake shoe in position to engage said drum to automatically prevent back motion of the set shaft, means for engaging said forward operating means and for applying the 25 brake, and means for causing the brake to engage the drum prior to the engagement of the forward operating means.

10. In a saw-mill setworks, the combination 30 of a set shaft, a ratchet wheel fixed thereon, an operating pawl for said ratchet wheel, a brake drum for said set shaft, a brake shoe in position to engage said brake drum to automatically prevent back motion 35 of the set shaft, and means for moving the pawl and brake-shoe into and out of engagement with the ratchet wheel and the brake drum, said means causing the brake shoe to engage the drum prior to the engagement of the pawl with the ratchet wheel.

In testimony whereof I affix my signature.

GEORGE E. CAMPBELL.
